US00D676337S

(12) **United States Design Patent**
Vulgamott et al.

(10) **Patent No.:** **US D676,337 S**
(45) **Date of Patent:** **** Feb. 19, 2013**

(54) **WRAP PACKAGING**

(75) Inventors: **Rick Vulgamott**, Brighton, MI (US);
Kristi Huffman, Grand Rapids, MI (US)

(73) Assignee: **Multi Packaging Solutions, Inc.**,
Lansing, MI (US)

(**) Term: **14 Years**

(21) Appl. No.: **29/427,652**

(22) Filed: **Jul. 20, 2012**

(51) **LOC (9) Cl.** **09-05**

(52) **U.S. Cl.** **D9/711**

(57) **CLAIM**

The ornamental design for a wrap packaging, as shown and described.

DESCRIPTION

FIG. 1 is a perspective view of packaging of the present teachings.

FIG. 2 is a top-down view of the embodiment shown at FIG. 1.

FIG. 3 is a bottom up view of the embodiment shown in FIG. 1.

FIG. 4 is a side elevational view of the embodiment shown in FIG. 1.

FIG. 5 is a side elevational view of the embodiment shown in FIG. 1.

FIG. 6 is a front elevational view of the embodiment shown in FIG. 1; and,

FIG. 7 is a rear elevational view of the embodiment shown in FIG. 1.

The broken lines showing environment in the drawings are for illustrative purposes only and form no part of the claimed design.
